FRANK MESKER AND THOMAS O. ARBEGUST, OF ST. LOUIS, MISSOURI,
ASSIGNORS TO MESKER & BROTHER, OF SAME PLACE.

WINDOW-FRAME.

SPECIFICATION forming part of Letters Patent No. 451,877, dated May 5, 1891.

Application filed May 3, 1890. Serial No. 350,532. (No model.)

To all whom it may concern:

Be it known that we, FRANK MESKER and THOMAS O. ARBEGUST, of St. Louis, Missouri, have jointly made a new and useful Improvement 5 in Window-Frame Construction, of which the following is a full, clear, and exact description.

The improvement relates to box-window frames more especially, and having the stiles 10 composed of sheet metal; and the improvement consists in the special means for uniting the inner face or edge of the stile with the adjacent construction, substantially as is hereinafter set forth and claimed, aided by 15 the annexed drawing, making part of this specification, in which the improved construction is shown in horizontal section taken between the top and bottom of the window-frame. Only those parts are shown which 20 are needed to an understanding of the improvement.

A A' represent the window-sashes.

B B' represent the stiles; C C', the inside finish-boards; D D', the studs of the adjacent 25 wall, in which the window-frame is contained, and E E' the adjacent columns. All these parts are constructed and united substantially as is exhibited in window-frame con-

structions, saving as modified by the particular improvement under consideration, which 30 is as follows: In the place of applying the stile to the outer edge of the finish-board and then applying a sash-stop to the outer side of the stile-edge, the finish-board C is extended at c to form a stop for the sash, and at c' is 35 grooved to receive the edge b of the stile, and the edge b is secured in the groove by means of nails b', applied substantially as shown. The stile-edge b is preferably flanged, as shown at b², and the groove c' is enlarged to 40 admit the flange. At its outer edge b³ the stile is secured either to the adjacent wall or column E in any suitable manner.

We claim—

The combination of the sashes, the sheet- 45 metal stile, and the finish-board, said finish-board being extended to form a sash-stop and grooved to receive the stile-edge, and said stile having the edge b inserted and nailed in said board-groove, substantially as described. 50
